ELECTRICAL DISPLAY DEVICE

James E. Brusha, Denver, Colo.

Application January 18, 1954, Serial No. 28,556

Term of patent 14 years

(Cl. D80—1)

To all whom it may concern:

Be it known that I, James E. Brusha, a citizen of the United States of America, residing at Denver, in the county of Denver and State of Colorado, have invented a new, original, and ornamental Design for an Electrical Display Device, of which the following is a specification, reference being had to the accompanying drawing, forming a part hereof.

In the drawing:

Fig. 1 is a side view of an electrical display device, showing my new design;

Fig. 2 is a top plan view thereof; and

Fig. 3 is a horizontal section, taken on the line 3—3, Fig. 1.

All four sides of the display device would be similar to the side shown in Fig. 1.

I claim:

The ornamental design for an electrical display device, as shown and described.
